CLAIM

The ornamental design for a lanyard connector, as shown and described.

DESCRIPTION

FIG. 1 is a perspective view of a lanyard connector showing my new design in use;

FIG. 2 is a perspective view of the lanyard connector shown in FIG. 1;

FIG. 3 is a top view of the lanyard connector shown in FIG. 1, the bottom view being a mirror image thereof;

FIG. 4 is a front view of the lanyard connector shown in FIG. 1;

FIG. 5 is a right side view of the lanyard connector shown in FIG. 1, the left side view being the mirror image thereof; and,

FIG. 6 is a rear view of the lanyard connector shown in FIG. 1.

The objects shown in broken, phantom lines are shown for environmental purposes only and form no part of the claimed design.
